[57] **CLAIM**

The ornamental design for a wick device for applying chemicals to weeds or plants, as shown and described.

DESCRIPTION

FIG. 1 is a view in perspective of the wick device showing our new design;

FIG. 2 is a front view thereof;

FIG. 3 is a partial front view thereof on an enlarged scale;

FIG. 4 is a top plan view thereof;

FIG. 5 is a partial top plan view thereof on an enlarged scale;

FIG. 6 is a bottom plan view thereof;

FIG. 7 is an enlarged left hand end view thereof; and

FIG. 8 is a rear view thereof.

The right hand end is a mirror image of the left hand end shown in FIG. 7.
